PRODUCTION OF ALKYL SUBSTITUTED
ARYL HYDROCARBONS

Charles A. Thomas, Wayne, Pa., assignor to The
Sharples Solvents Corporation, Philadelphia,
Pa., a corporation of Delaware

No Drawing. Application August 28, 1933,
Serial No. 687,246

4 Claims. (Cl. 260—168)

The present invention relates to the alkylation of aryl hydrocarbons by the substitution of alkyl radicals of relatively high carbon content for nuclear hydrogen of such hydrocarbons. It is more particularly concerned with the production of alkyl substituted aryl hydrocarbons having from eight to thirty carbon atoms in the alkyl side chain. It is the object of the invention to produce compounds of this type by a commercially feasible process affording a high yield of the desired compound by a relatively inexpensive procedure. Important economies are attained in the performance of the process by reason of the fact that it may be performed in relatively inexpensive apparatus and because the unused products are recovered in a form which makes possible their reuse in a repetition of the process.

The process of the invention is based fundamentally upon the well-known Friedel and Crafts reaction by which alkyl chlorides are condensed with substituted or unsubstituted aryl hydrocarbons in the presence of anhydrous aluminum chloride or other equivalent catalyst. It involves the initial step of chlorinating paraffin hydrocarbon material of the desired carbon content or range and the condensation of chlorinated hydrocarbon material with an aryl compound in the presence of a catalyst.

A number of difficulties are encountered in connection with attempts to perform such a series of operations in the production of alkyl chlorides of high molecular weight and the subsequent separation of mono-chlorides so formed from unreacted paraffin hydrocarbons and poly-chlorides.

The performance of the chlorination operation by a procedure involving the conversion of the major portion of the hydrocarbon into chlorides necessarily results in the production of a large proportion of undesired poly-chlorides. Even in cases in which chlorination is terminated long before a molecular proportion of chlorine has combined with the hydrocarbon, a great deal of undesired formation of polychloride material occurs when the chlorination reaction takes place in metal apparatus of other apparatus tending to catalyze the splitting of the monochlorides formed to produce olefins and hydrochloric acid, as olefins so formed have a tendency to promptly combine with more chlorine to produce undesired dichlorides. If the chlorination operation is not carried to substantial completion, serious problems of distillation are also encountered in separation of unreacted paraffin hydrocarbons from the chlorides preparatory to the subsequent step

in which the chlorides are condensed with the aryl hydrocarbon.

The higher molecular weight chlorides which are to be used in the condensation reaction are so close in boiling range to the hydrocarbons from which they are derived that they can only be separated from the unreacted hydrocarbons with great difficulty. In some instances of chlorination of mixtures of isomeric paraffin hydrocarbons these ranges actually overlap each other, and in such instances efficient separation is extremely difficult. A further difficulty is encountered by reason of the fact that a large proportion of these alkyl chlorides are decomposed when they are heated in metal apparatus. Attempts at distillation in such apparatus accordingly result in undesired splitting of much of the chlorinated material to produce olefins and hydrochloric acid. In order to avoid splitting in such an operation, it is necessary that the distillation be conducted in apparatus made of glass or other expensive inert material which does not act as a catalyst to cause the splitting of the chlorides.

In the practice of the present invention the paraffin hydrocarbon material is first chlorinated to produce a mixture of hydrocarbons and chlorides. The chlorination of the hydrocarbon may be performed by passing gaseous chlorine into a mass of liquid hydrocarbon and this chlorination operation is discontinued long before combination of a molecular equivalent of chlorine with the hydrocarbon under treatment. This chlorination operation is performed in apparatus of glass or other non-metallic material in order that decomposition of chlorides formed in the reaction, and subsequent formation of poly-chlorides may be substantially completely avoided. By observing these precautions, the production of any large amount of polychloride material is avoided.

At the conclusion of the operation in which the hydrocarbon material is partially chlorinated, the entire mass of mixed chlorides and paraffin hydrocarbons is mixed with the aryl hydrocarbon with which it is to be condensed. It is to be noted that no attempt at separation of paraffin hydrocarbons from chlorides is made prior to this operation. The mixture of aryl hydrocarbon, alkyl hydrocarbons and alkyl chlorides is next stirred during the addition of a sufficient quantity of anhydrous aluminum chloride or other equivalent catalyst to effect condensation of the alkyl chlorides with the aryl hydrocarbon in accordance with the Friedel and Crafts reaction. At the conclusion of the condensation reaction, the com-

plex is decomposed with dilute hydrochloric acid or cold water and the mixture distilled until the unused hydrocarbon is recovered, and further distilled to effect separation of the desired alkyl 5 substituted aryl hydrocarbon from the residue.

In a typical example of the practice of the invention, the following procedure was adopted:

1000 grams of mixed paraffin hydrocarbon material consisting principally of dodecane was partially chlorinated by bubbling chlorine through the material until it had gained 70 grams in weight; i. e., until approximately 35% of the hydrocarbons had been converted to monochlorides. 3 liters of benzene were added to the mixture of chlorides and paraffin hydrocarbons and the mixture was stirred during the addition of 200 grams of anhydrous aluminum chloride. After one-half hour the complex was decomposed by the addition of a small amount of dilute hydro- 10 chloric acid and the mixture was steam distilled until all of the unused benzene had been recovered. The residue was then vacuum distilled and yielded 660 grams of hydrocarbon material. Tests with bromine water indicated that this 15 hydrocarbon was saturated and could hence be used in a second chlorination and condensation in connection with a repetition of the process. 238 grams of material having a boiling range from 185-210° C. at 25 mm. pressure and consisting principally of lauryl benzene was recovered. A residue of 98 grams which is believed to have comprised principally dilauryl benzene, was obtained.

It will be noted that the practice of the invention in accordance with the above described procedure involves avoidance of the loss of valuable paraffin hydrocarbon and other difficulties incident to the formation of dichlorides such as would be encountered in connection with attempts to effect more complete chlorination of the hydrocarbon mixture or chlorination in metal apparatus and that the use of the entire mixture of chlorides and paraffin hydrocarbons in the subsequent step of condensation with the aryl hydrocarbon obviates the difficult problems of fractionation referred to above. While great difficulty would be encountered in attempts to separate the unreacted paraffin hydrocarbon material from corresponding chlorides, the separation 40 of this material from the alkyl substituted aryl compounds by distillation is not difficult, as these last-mentioned compounds have boiling ranges much higher than the paraffins or chlorides used in the condensation reaction.

55 Modifications will be obvious to those skilled in the art and I do not therefore wish to be limited except by the scope of my subjoined claims. The chlorination may, for example, be carried out in the vapor phase provided a substantial molecular 60 excess of hydrocarbon is used. In the interpretation of the claims, I wish it to be understood that the term "aryl compound" is intended to include not only unsubstituted aryl hydrocarbons, such as benzene and naphthalene, but also such substituted derivatives of these compounds as are capable of condensation with alkyl chlorides in accordance with the Friedel and Crafts reaction.

What I claim is:

1. The method of producing a mass of material comprising essentially a mono-alkyl derivative of an aryl compound which comprises chlorinating paraffin hydrocarbon material corresponding in carbon content to the alkyl radical of the desired derivative to an extent sufficient 70 to produce a mixture of the paraffin hydrocarbon

and the corresponding alkyl monochloride but insufficient to produce any substantial quantity of alkyl poly-chlorides, mixing the mixed mass of alkyl chloride and paraffin hydrocarbon with the aryl compound which is to form the aryl radical 5 of the desired derivative, condensing the alkyl chloride of the mixture with the aryl compound and thereafter separating the uncondensed material from the desired derivative by distillation to obtain a mass of the desired alkyl derivative substantially free of paraffin hydrocarbon and chlorine derivatives.

2. The method of producing a mass of material comprising essentially a mono-alkyl derivative of an aryl compound containing from eight to twenty 15 carbon atoms in its alkyl radical which comprises chlorinating paraffin hydrocarbon material corresponding in carbon content to the alkyl radical of the desired derivative to an extent sufficient to produce a mixture of the paraffin hydrocarbon 20 and the corresponding alkyl monochloride but insufficient to produce any substantial quantity of alkyl polychlorides, mixing the mixed mass of alkyl chloride and paraffin hydrocarbon with the aryl compound which is to form the aryl radical 25 of the desired derivative, condensing the alkyl chloride of the mixture with the aryl compound and thereafter separating the uncondensed material from the desired derivative by distillation to obtain a mass of the desired alkyl derivative substantially free of paraffin hydrocarbon and chlorine derivatives.

3. The method of producing a mass of material comprising essentially a mono-alkyl derivative of an aryl compound which comprises chlorinating paraffin hydrocarbon material corresponding in carbon content to the alkyl radical of the desired derivative to an extent sufficient to convert a part but less than one-half of the material into the corresponding alkyl mono-chloride while avoiding production of any substantial quantity of alkyl polychlorides, mixing the resulting chloride together with the unreacted hydrocarbon with the aryl compound which is to form the aryl radical of the desired derivative, condensing the alkyl chloride of the mixture with the aryl compound and thereafter separating the uncondensed material from the desired derivative by distillation to obtain a mass of the desired alkyl derivative substantially free of paraffin 40 hydrocarbon and chlorine derivatives.

4. The method of producing a mass of material comprising essentially a mono-alkyl derivative of an aryl compound which comprises chlorinating paraffin hydrocarbon material corresponding in carbon content to the alkyl radical of the desired derivative to an extent sufficient to produce a mixture of paraffin hydrocarbon and the corresponding alkyl mono-chloride but not sufficient to produce any substantial quantity of 55 alkyl poly-chlorides, mixing the resulting mass of alkyl chloride and paraffin hydrocarbon with the aryl compound which is to form the aryl radical of the desired derivative, condensing the alkyl chloride of the mixture with the aryl compound 60 and thereafter separating the uncondensed material from the desired derivative by distillation to obtain a mass of the desired alkyl derivative substantially free of paraffin hydrocarbon and chlorine derivatives, said process being carried out 70 while maintaining the reactants out of contact with materials, such as various metals, that cause the formation of undesirable compounds.
